METHOD AND MECHANISM FOR GENERATING GEARS, RACKS AND THE LIKE
Giordano Romi, Santa Barbara d'Oeste,
Sao Paulo, Brazil
Filed July 10, 1957, Ser. No. 671,095
10 Claims. (Cl. 90—7)

The present invention relates to a new method and apparatus for cutting cylindrical gears and racks, by means of the well known generation method, in which a tooth profile, rolling in synchronism and coupled to a moldable piece, will "generate" on this moldable piece the exact tooth profile suitable for engagement with itself; in the same way, a gear wheel having a series of tooth profiles with suitable cutting edges "generates" on a wheel disc a corresponding series of tooth profiles which will be able to engage with itself, provided that the two wheels are turning in synchronism and that the gear wheel have reciprocating movements. The profiles of the cutting wheel teeth being involute profiles, in the teeth of the generated wheel there will be reproduced involute profiles.

The new method, chief object of this invention, which is apparently similar to the conventional ones, and makes use of the properties of the involute curve, is nevertheless, basically different from all previously existing methods, because of the type of cutter and machine or machines used, and because of the utilization of the cutting cycle; said cutter and machine or machines when considered as a whole, enable the practical realization of the new method and apparatus for cutting gears and/or racks in accordance with the invention, as it will be pointed out below in connection with the further objects of the invention.

Another object of the invention is to apply the new method to a new generating gears mechanism which enables the generation of two or more stacks of cylindrical gear wheels with straight or helical teeth, mounted on two different turning shafts with substantial saving of time in the useful cutting cycle.

A further object of the invention is to provide the necessary reciprocating movements in the moulding generation method in such a way that the chief reciprocating movement by means of which the cutting action is performed, is transmitted to a secondary longitudinal reciprocating movement of the turning axis of the cutting gear wheel, by means of which the cutter is alternatively approached and spaced from the piece to be cut.

A still further object of the invention is relative to the fact that when the new method is applied to the new cutting gears mechanism, it is possible to continuously cut the gears, that is to say to cut the gears without stopping the machine; this is due to the fact that it is possible to mount a group of gears to be cut on any one of the two generation stations while on the other generation station is being processed the cutting operation of the other group of gears to be cut. In this way is saved the time for removing and mounting the pieces, normally required in the conventional methods.

Another object of the invention is to allow the use, during the generation operation, of cutting depths and advances substantially heavier than the normally allowable in the conventional methods and machines. This is due to the fact that the new machine has high rigidity conditions because the principle on which it is based enables its construction with a substantially reduced number of movable members.

A still further object of the invention is related to the fact that without altering the basic conditions of the method it is possible to perform the cutting of racks with

2

the machine used to cut gears; for this purpose it is sufficient to change the rotatory movement of the gear supporting shaft into a linear movement by means of the application, on said gear supporting shaft, of a suitable device.

A further object of the invention is to apply the invented method to a new straight teeth racks generating machine which has absolutely new and original characteristics.

10 A still further object of the invention is to apply the invented method to a new helicoidal teeth racks generating machine which has also absolutely new and original characteristics.

15 Another object of the invention is to make the cutter used in the new method as actually consisting of a suitably characterized gear wheel, like a master gear, with envelope profile teeth, which allows to obtain the same results as obtained by the conventional methods, keeping present the following basic conditions.

20 For cutting gears:

(1) To create on one or both faces of the gear wheel (cutter)—cutting face or faces—a conical surface which geometric axis is coaxial with the geometric axis of the wheel and having a suitably dimensioned vertex angle.

25 This conical surface is obtained on sharpening the gear wheel (cutter), in such a way that the cutting edges of the teeth are formed by the intersection of said conical surface with said teeth.

(2) To incline the turning axis of the gear wheel (cutter) through a suitable angle in relation to the turning axis of the gear blank or blanks, and through the same angle in relation to the direction of the main reciprocating movement.

30 (3) To keep unchanged the inclination angle cited in (2) during the reciprocating action of the gear wheel (cutter), the turning axis of the gear wheel (cutter) and of the gear blank or blanks, being coincidental with a plan which coincides with the main reciprocating movement direction, parallel to the turning axis of the gear blank or blanks, and with the secondary reciprocating movement direction, parallel to the turning axis of the gear wheel (cutter).

For cutting racks:

35 (1) To create on one face of the gear wheel (cutter)—cutting face—a conical surface the geometrical axis of which is coincident (coaxial) with the geometrical axis of the wheel, and having a suitably dimensioned vertex angle. This conical surface is formed by sharpening

50 the cutter in such a way that the cutting edges of the teeth of the gear wheel (cutter) are formed by the intersection of said conical surface with said teeth.

(II) To incline the gear wheel (cutter), that is to say to incline all the plans perpendicular to the turning axis 55 of the gear wheel (cutter) through a suitable angle in relation to the plan which contains the longitudinal axis of the blank rack at the moment in which this plan coincides with the generation plan.

(III) The direction of displacement for generating the 60 rack is to be parallel to the intersection of any plan perpendicular to the axis of the gear wheel (cutter) with the generation plan, that is to say, it is to be parallel to the longitudinal axis of the blank rack.

(IV) To impart a reciprocating movement in a direction perpendicular to the longitudinal axis of the rack, this direction making, with the turning axis of the gear wheel at the generation act the same angle as defined in (II).

(V) To keep substantially constant the inclination 65 angle of the gear wheel (cutter), as defined in (II).

A still further object of the present invention is to allow the use of a pattern gear with helicoidal teeth of

suitable characteristics as gear wheel (cutter) in the application of the new method, as a result of which helicoidal gears or racks may be generated.

Another object of the present invention is to avoid the use of additional devices required in the conventional methods, in order to obtain some special characteristics; this is automatically done when the invented method is applied to the new racks generating mechanisms.

Another object of the invention is to provide that by using as cutter a pattern gear wheel of suitable characteristics, and by observing the basic conditions (1), (2), (3), and (I), (II), (III), (IV), (V), it is no more necessary that the flanks of the cutter's teeth are formed by involute helicoid surfaces, or like surfaces specially developed as occurs by using the known processes; similarly, it is no more necessary that the heads of the teeth have such an exit angle that their widths, through any plane perpendicular to the turning axis of the cutter are kept approximately constant; it is also no more necessary to keep approximately constant the cutting depth during all the useful life of the cutter, neither is it any longer necessary that the teeth profiles are specially determined and corrected in order to ensure, after each sharpening, cutting characteristics more or less constant.

A still further object of the invention is to allow that the gear wheel (cutter) works during all its life and even after several sharpening operations always with constant operating or cutting pressure angle, differently from the conventional methods, which are characterized by the fact that they operate with cutting or operating pressure angles which are changed after each sharpening operation.

A still further object of the invention is to facilitate the construction of the cutter (pattern gear wheel) used in connection with the new method, without using any specially designed equipment, but using only the ordinary standard machinery which is normally employed to cut and rectify precision cylindrical gears.

Another object of the invention is to use the same ideas and the same basic principles in order to create a number of machines intended to be employed for various purposes in the art.

A still further object of the invention is to obtain that the new method for cutting teeth, applied to new mechanisms, have all the advantages and allow all the applications for gear and racks generations purposes which are actually performed by the existing similar machines; besides, the new method may be employed for cutting pieces of various different shapes, always making use of the generation principle.

Other advantages and further objects of the present invention will be evident from the following description, which is made in connection with the appended drawings, and given, both description and drawings, by way of non-restrictive example.

FIG. 19 diagrammatically shows the relative positions of the gear wheel (cutter) and of the rack blank, at the generation act.

FIG. 19a shows projections of a tooth, and FIG. 19b is a sectional view taken on line P—P in FIG. 19a.

FIG. 20 diagrammatically shows the relative positions of the gear wheel (cutter) and of the piece to be cut, and FIG. 20a shows several projections of a tooth of the gear wheel (cutter) on the generation plane;

FIG. 21 diagrammatically shows the relative positions of the gear wheel (cutter) and of the blank gear at the generation act, with projection of this position on the generation plan G—G.

As represented in FIGURES 1, 2, 3, 4, 5 and 6, the machine for cutting teeth in cylindrical gears to which was applied the new method in accordance with the invention, consists of a body 1, with two parallel vertical guides 2, along which is movable the head 3 of the machine, in both the senses indicated by the arrows Y_1 and Y_2 , and in a direction parallel to the longitudinal axis of the vertical guides 2; said body 1 is also provided, at its lower part, which constitutes the base 4 of the machine, with two other horizontal parallel guides 5, which have their longitudinal axis disposed perpendicularly to the plane formed by the vertical guides 2; on these horizontal guides 5 and in a direction parallel to their longitudinal axis, are movable the blank gear supporting tables 8 and 8a.

Each table 8 and 8a supports the wheel or group of wheels 9 and 9a on which the teeth are to be generated by turning them about their geometric axes $Y—Y$ and $Y_a—Y_a$, respectively; these axes are parallel and contained in a plane which is parallel to the plane of the vertical guides 2 and consequently is perpendicular to the plane of the horizontal guides 5. The turning axes $Y—Y$ and $Y_a—Y_a$ are, consequently, parallel to the di-

rection of displacement of the head 3, indicated by arrows Y_1 and Y_2 .

The head 3 of the machine supports the main shaft 10 to which is fixed the cutter 11; the turning axis X—X of this cutter coincides, therefore, with the geometric axis of the shaft 10. The turning axis X—X is coplanar with the turning axes $Y—Y$ and $Y_a—Y_a$ of the wheels 9 and 9a and forms with the axes $Y—Y$ and $Y_a—Y_a$ an angle α ; consequently the axis X—X forms with the vertical guides 2 and with the direction of displacement of the head 3, which is marked by arrows Y_1 and Y_2 , the same angle α . This angle α is kept unchanged during the displacements of the head 3 with the shaft 10 and the cutter 11 along the vertical guides 2.

The displacement of the cutter 11 with the shaft 10 and the head 3 in the senses marked by arrows Y_1 and Y_2 constitutes the "main—or cutting—reciprocating movement" of the cutter 11, needed in connection with the molding generation method.

The position of the turning axis X—X of the cutter inclined at an angle α to the turning axes $Y—Y$ and $Y_a—Y_a$ of the blank wheels, and consequently, at the same angle α to the direction of displacement marked by arrows Y_1 and Y_2 is the basic characteristic of the new method and apparatus for cutting gear teeth according to the present invention. As a matter of fact, all the similar conventional methods of generating cylindrical gears with straight or helicoidal teeth, based upon the known principle of molding generation with reciprocally movable circular cutters, require, as fundamental condition, that the turning axes of the cutter and of the gear blank are parallel to each other and to the direction of the main reciprocating movement.

The upper end 10a of the shaft 10, over which is transmitted—as will be pointed out later—the rotatory movement to the cutter (11) has—during the reciprocating movement of the head 3 along the vertical guides 2 in either the senses marked by arrows Y_1 and Y_2 , and as a result of this movement—a horizontal displacement movement respectively in either the senses marked by arrows $6a$ and $7a$ (FIGS. 3, 4 and 11). Said upper end 10a is, therefore, supported by the movable slide 12 which has two horizontal guides 13, parallel to each other, and which may be displaced on two corresponding channels 14, the longitudinal axis of which are coplanar with the longitudinal axis of the horizontal guides 5.

On the other hand the shaft 10 and consequently also the gear cutter 11, fixed to the first, may move along the turning axis X—X in either the two senses marked by arrows X_1 and X_2 . This movement constitutes the secondary reciprocating movement of the gear cutter 11, in the molding generation process, as will be later explained in detail.

In order to ensure the free transmission of the rotatory movement of the gear cutter 11, during the displacement of the head 3 in either the two senses marked by arrows $Y_1—Y_2$, while the movable slide 12 is moved with its mechanism respectively in either the two senses marked by arrows $6a$ and $7a$, the endless worm screw 32 is provided, which can axially move in either the two senses marked by arrows $6a$ and $7a$ along the grooved shaft 31 together with the slide 12 (FIGS. 3 and 4). Worm screw 32 is mounted on head 12 non-movable in direction $6a$, $7a$.

With reference now to FIG. 11, the reasons of the movement of slide 12 in either the two senses marked by arrows $6a$ and $7a$ will be explained.

It is to be noticed that the main cutting reciprocating movement is effected by cutter 11 in the direction shown by arrow M, from point Q to point Q', the distance M between Q and Q' being equal to the distance M_1 , covered by head 3 in its corresponding movement.

Head 3 moves in the sense of the arrow Y_2 during its movement from Q^4 to Q^5 over the distance M_1 .

Head 3, going from Q^4 to Q^5 carries the shaft 10; hav-

ing this shaft 10 an inclination angle α with the displacement direction, shown by arrows M_1 or Y_2 , the axis S of it is consequently displaced to S_1 .

Since the worm wheel 33 and shaft 10 are turnably mounted in slide 12, this slide 12 is obviously caused to move from S_2 to S_3 together with shaft 10 and over a distance which is equal to $S—S_1$ in direction of arrows $6a$, $7a$.

The movement in the direction of arrows M_1 and M 10 was downwardly performed by head 3.

When head 3 moves upwardly, from point Q^6 to Q^7 , in the direction of arrows M_3 and Y_1 carrying the shaft 10 and its cutter 11, and consequently displacing the cutter from Q^2 to Q^3 , the axis S_1 of the shaft 10 returns to its initial position S and—as previously explained—carries the head 12 in the direction of arrow $7a$ from position S_3 to position S_2 .

It is to be noticed that the movements $Q^4—Q^5$, $Q—Q^1$ and $Q^6—Q^7$, $Q^2—Q^3$ are main reciprocating movements; 20 the secondary movements have been up to now omitted because they do not cause any displacement of slide 12 and shaft 10 in the direction of arrows $6a$ and $7a$ and will be explained later.

Means for driving the rotatory movement of the gear 25 cutter 11 and of the blank gears 9 and 9a are diagrammatically represented in FIG. 6. References therefore will be made to this figure and to the aforesaid FIGURES 1, 2 and 3. The power of the electric motor is transmitted—over a change speed gear box 16, which 30 allows the work at several speeds—to a shaft 19, to which is fixed a bevel gear 17; this bevel gear 17 engages with another bevel gear 18, and thus the movement is transmitted to the mechanism of the slide 12, as explained below. At the same time, the shaft 19 transmits power 35 and rotatory movement to the bevel gear 20, which is coupled to the bevel gear 21; this bevel gear 21 is fixed to the shaft 22, by means of which the movement is transmitted to the mechanisms of the tables 8 and 8a, as will be explained below.

40 As the transmission relationship between gears 17—18 and 20—21 is 1:1, the horizontal shaft 22 and the vertical shaft 23 will revolve at the same angular speed. The horizontal shaft 22 transmits power and movement to the gears of the gear boxes 24 and 24a provided at the base 45 of the machine; these gear boxes retransmit the power and the movement by means of the grooved shafts 25 and 25a to the endless worm screws 26 and 26a which, in turn, further transmit said power and movement to the helicoidal worm gears 27 and 27a; said helicoidal gears 50 are turning about the turning axis $Y—Y$ and $Y_a—Y_a$ with the shafts 28 and 28a, to which are fixed the gear blanks 9 and 9a. Power and movement are thus transmitted from motor 15 to gear blanks 9 and 9a.

In order to assure that the rotatory movement to the 55 gear blanks 9 and 9a is transmitted independently of the displacement of tables or carriages 8 and 8a in either of the two senses marked by arrows 6 and $7a$, the endless worm screws 26 and 26a are slidably mounted on the grooved shafts 25 and 25a.

60 To the vertical shaft 23 is also fixed the bevel gear 29, which engages with the bevel gear 29a, fixed to a shaft 29b.

On the shaft 29b is fixed the bevel gear 30 engaged with the bevel gear 30a; this gear 30a transmits power 65 and movement to the grooved shaft 31, on which slides the endless worm screw 32 which meshes with the helical worm gear 33, the turning axis X—X of which forms an angle of $(90^\circ - \alpha)$ with the axis of worm screw 32. The worm gear 33 is mounted near the upper end 10a of the shaft 10, in such a manner that this shaft can slide in both the senses marked by arrows X_1 and X_2 while receiving from worm gear 33 the transmitted rotatory movement about the axis X—X of the gear cutter 11, which, therefore, turns with the shaft 10.

Since the transmission of power and of rotatory move-

ment from shaft 19, over 23, 29b, 31 to the shaft 10, to which is fixed the gear cutter, is effected in a positive and fixed relationship, shaft 10 and shaft 19 will always turn in the same relationship.

The transmission of power and rotatory movement—from shaft 19, over shaft 22, shafts of the gear boxes 24 and 24a, and shafts 25 and 25a, to the shafts 28 and 28a on which are fixed the gear blanks 9 and 9a—is effected in such a manner that the transmission ratio can be changed. The changes in the transmission ratio between shaft 19 and shafts 28 and 28a are carried out by means of the gear boxes 24 and 24a. The changes in the transmission ratio allow—within the limits of the machine's capacity—the synchronization of a great number of gear blanks with quite different members of teeth to be cut—with the gear cutter 11.

In fact, on cutting a given gear with n teeth by means of a gear cutter with n_1 teeth, it will be sufficient to multiply the relation $n_1:n$ by the machine relationship, to find the corresponding gears and to put them into the gear boxes 24 or 24a. The manner in which these gear ratios can be found is well known and does not constitute an object of the present invention. The machine, therefore, allows to mold at the same time gear blanks 9 and 9a with the same or with different numbers of teeth.

Hydraulic control means are provided to permit operation at the various possible different speeds and strokes of the main reciprocating movement of the head 3 and of the gear cutter 11 in either the two senses marked by arrows Y_1 and Y_2 , and at operator's choice in accordance with specific requirements with secondary reciprocating movement of the gear cutter in either the two senses marked by arrows X_1 and X_2 . The hydraulic control means control the movements of the carriages 8 and 8a in either the two senses marked by arrows 6 and 7; and finally are capable to slowly move for adjustment purposes the head 3 in either the two senses marked by arrows Y_1 and Y_2 . The construction of the hydraulic system is not part of this invention.

The suitable synchronization of the main and secondary reciprocating movements is also performed by means of the hydraulic system the construction of which does not form part of the present invention, and this synchronization will be explained below.

The hydraulic control system for operation and synchronization of the reciprocating movements of the head 3 and of the shaft 10 will be now described with reference to the FIGURES 7, 8, 9, 10 of the drawings.

The hydraulic control system consists of: A valve 101, for reversing the main and secondary reciprocating movements. A stationary piston 102, fixed to the body 1 of the machine. A piston 103, fixed on the shaft 10 which can move in either the two directions X_1 and X_2 (secondary reciprocating movement). The head 3 of the machine, which moves in the directions Y_1 and Y_2 (main reciprocating movement). The check valves 104 and 105 which allow the oil to pass only in the directions marked by the arrows 106 and 107 respectively.

To operate the head 3, the oil can enter alternatively through openings 110 and 111.

To operate the piston 103 the oil can enter alternatively through openings 108 and 109.

The valve 101 consists of a piston 117 which can be axially moved, said valve 101 having an oil inlet 119 through which the oil is fed under pressure by means of a pump (not represented in the drawings), two oil outlets 120 and 121 for discharging purposes, and two openings 122 and 123 which, depending upon the position of the piston 117, can serve as an oil inlet from the pump (see FIG. 7) to the chambers 124—126 and as an oil outlet from the chambers 128—127 (as represented in FIG. 7) or, alternatively (see FIG. 8) as an oil outlet from the chambers 124—126 and as an oil inlet to the chambers 128—127.

The piston 117 is operated by means of the lever 112, which bears on point 113 and can move in the senses marked by arrows 114a and 114b.

The lever 112 is operated by means of the stop latches 115 and 116 fixed to the head 3 and which can be mounted in different positions in order to regulate the head run in the main reciprocating movement. Reversing the main reciprocating movement is effected when any one of the stop latches 115 or 116 abuts the end 112a of the lever 112, during the movement of the head 3 in either the two senses Y_1 and Y_2 .

Let us assume that the head 3 of the new gear generating machine is near the end of the main upward reciprocating movement and beginning of the secondary downwards reciprocating movement, as diagrammatically represented in FIG. 7.

As shown by the arrows, the oil enters through pipe 119 into the annular chamber 140 and through the outlet 122, after passing through passage 109, enters the annular chamber 124 which is part of the cylindrical housing of piston 103 associated with the secondary reciprocating movement.

From chamber 124 the oil can pass to the annular chamber 126 through passages 125 and 110. As indicated by the arrows, from chamber 127, which is the lower part of the cylindrical housing of the main reciprocating movement, the oil goes out through passage 111, passes freely through valve 104, enters the chamber 141 through the passage 123 and is discharged through pipe 121. As also indicated by the arrows, the oil is discharged from chamber 128 through passage 108, passage 123, chamber 141 and pipe 121.

The stop latch 115 abuts the end 112a of the lever 112 and as a result of the movement of head 3 in the direction of the arrow Y_1 due to the oil pressure exerted on face 126a of piston 102 within the chamber 126, will lift said lever, as will be explained in connection with FIG. 8.

In FIG. 8 the head 3 is in its extreme ascending position and having the stop latch cooperated with the end 112a of lever 112, has lifted this one in the direction of arrow 114a.

The lever 112 on moving in the cited direction has carried the piston 117 as a result of which the oil flow is changed from the passage 122 to the passage 123, as indicated by the arrows.

Through passage 123, as indicated by the arrows, and through inlet 108, the oil reaches the chamber 128, displacing the piston 103 to which is fixed the shaft 10 and gear cutter 11 a distance D, until the face 124a of piston 103 abuts the face 124b of the cylindrical housing. During its travel, the piston 103 opens the passage 129, through which the oil can enter the chamber 127, after having passed through passage 111. From chamber 124, as indicated by the arrows, the oil passes through passage 109 and is discharged through passage 122, valve 101 and pipe 120. From chamber 126, as indicated by the arrows, the oil passes through passage 110, passes freely through valve 105 and is discharged through passage 122, chamber 141a, valve 101 and pipe 120.

The main downwards reciprocating movement begins with the oil pressure exerted on faces 127a and 127b.

Hence the head 3 moves in the direction of arrow Y_2 (see FIG. 9) until the stop latch 116 abuts the end 112a of lever 112, causing the displacement of piston 117 and thus initiating the reversion of said displacement.

The stop latch 116, abutting the end 112a of lever 112, causes the lever 112 to move in the direction of arrow 114b. Lever 112 carries the piston 117 and enables the oil to go out from chamber 140 through passage 122, as represented in FIG. 10.

The oil flowing through passage 122 reaches passage 109 and enters the chamber 124, thus initiating the secondary upwards reciprocating movement. The oil pressure on the faces 124a and 124 causes the piston 103 to rise until its face 128a abuts face 128b; the oil can now

enter the chamber 126 through passages 125 and 110, thus initiating the main upwards reciprocating movement.

From chamber 128, as indicated by the arrows, the oil passes to passage 108 and is discharged through passage 123, chamber 141 and pipe 121.

From chamber 127, as indicated by the arrows, the oil passes to passage 111, goes freely through valve 104, passes through passage 123 and is discharged through chamber 141 and pipe 121.

The construction of the "above described hydraulic control system for operating and synchronizing" the reciprocating movements of head 3 and shaft 10 is not an object of the present invention; the synchronization of said reciprocating movements of head 3 and shaft 10 can be performed by means of several different methods and devices, as is well known by those skilled in the art.

The machine is also provided with manual controls which do not form part of the present invention, and serve for operating head 3 and carriages 8 and 8a for adjustment purposes only.

The new machine is also provided (see slide 12, FIG. 5) with a device which is not an object of this invention and serves to substitute the bushing of shaft 10, which is divided into two parts by means of a cut through the axis X-X, for a two parts bushing 33a and 33b; one of these parts is fixed to shaft 10 and the other is fixed to slide 12 and they are obtained by cutting a bushing through an helice plotted on its cylindrical surface. The two bushings allow to combine the turning movement of the shaft with an helicoidal movement when the new machine is used with a gear cutter 11 with helicoidal teeth, in order to produce helicoidal gears.

The gear cutter 11 employed in this machine and which is diagrammatically represented in FIG. 14, is a cylindrical gear wheel of suitable predetermined characteristics like a master gear as usually employed in high precision cutters. It is made of suitable material and has straight or helicoidal teeth, depending upon the specific requirements. The profile of the teeth of the gear wheel employed as gear cutter 11 has involute shape.

Only for non restrictive explanations purposes, all the following considerations on the cutting action of the gear cutter 11 and on the generated gear and/or racks are based upon the assumption that the teeth of the gear cutter 11 and the teeth of the gear or rack to be cut are straight. Corresponding considerations may be applied to the case in which said teeth are helicoidal, provided that the necessary basic alterations are made, as is usual in the conventional processes.

The gear cutter 11, as used in the previously described machine in accordance with this invention, is shown in FIGS. 14a and 14b and has in both its faces 34 and 34a, a conical surface 35 the generating line of which makes an angle β with the faces 34 and 34a. This conical surface, the geometric axis of which coincides with the turning axis of the gear cutter 11, is obtained by the sharpening operation of the gear cutter, in such a manner that the intersection of said surface 35 with the teeth 36 forms the cutting edges of the cutter 11.

A gear cutting operation will now be described referring to FIG. 12, in which is represented the relative position of the gear cutter 11 and of the gear blanks 9 and 9a to be generated, as assumed in connection with the invented method and applied to the new gear generating machine.

The gear blanks 9 and 9a, on which the teeth are to be cut, turn about their respective turning axes Y-Y and Ya-Ya suitably synchronized with the gear cutter 11, which rotates about its turning axis X-X, as previously pointed out.

For construction and explanation facility purposes, and without restricting the method of the present invention, the gear blanks 9 and 9a are mounted in the position represented in FIG. 12, in such a manner that the upper faces 9b and 9c of them coincide with two planes, parallel

to each other and parallel to the planes which contain (see FIGS. 1, 2, 3) the longitudinal axis of the guides 5; the distance L between said two planes is suitably selected.

For explanation simplicity purposes and without restricting the invented method, the cutting of the teeth of wheels 9 and 9a will be separately examined, beginning with wheel 9.

During the cutting cycle, the cutter 11 successively assumes the positions A, A₁, B, B₁ and A of FIG. 12.

10 In position A, which only for explanation purposes will be named initial position of the reciprocating cutting cycle of wheels 9, the cutting edge 36a of the tooth 36 is at a distance d from the bottom 37 of the teeth to be cut in the wheels 9; these wheels were previously and suitably fed (together with the carriage 8, not represented in FIG. 12) through the suitable cutting depth until they reached the position represented in FIG. 12. During all their cutting cycle the wheels 9 will remain in this position and will turn about their axis Y-Y in synchronization with the cutter 11, as previously explained.

20 At the beginning of the secondary reciprocating movement of the cutter 11, this cutter 11 moves axially in the direction of the arrow X₂ through a distance D until it reaches the position A₁ in which the cutting edge 36a is tangent to the teeth bottom land 37, the distance d being reduced substantially to zero. At this point, the secondary reciprocating movement of cutter 11 finishes and begins the main reciprocating movement of cutter 11 (beginning with the cutter moving together with the shaft 10 and the head 3 (which are not represented in FIG. 12), in the direction marked by arrow Y₂). The main reciprocating movement in the direction of arrow Y₂ effects the cutting operation of the cutting edge 36a, which after having gone through the maximum distance M determined by the thickness of the blank wheel or wheels 9, finishes its cutting action on the bottom land 37 of the teeth to be cut, when the cutter 11 reaches its position B. Thereupon the return stroke of the secondary reciprocating movement of the cutter 11 begins, which moves 30 in axial direction thereof through a distance D in the direction marked by arrow X₁, until it reaches the position B₁; in this position the cutting edge 36a will be again at a distance d from the bottom land of the teeth to be cut in the wheel or wheels 9. At this moment, the second 35 stroke of the secondary reciprocating movement is terminated and the second stroke of the main reciprocating movement of the cutter 11—together with the shaft 10 and the head 3, not represented in FIG. 12—begins in the direction shown by arrow Y₁. This movement finishes when cutter 11 with the cutting edge 36a—having gone through the distance M—returns to the initial position A. At this moment a cutting reciprocating cycle is completed. By repeating this cycle as many times as it is required while the gear cutter 11 and the gear blank or 40 blanks 9 are turning about their respective axes X-X and Y-Y, all the teeth will be generated, the number of cycles depending upon known relations and values which do not form part of this invention. As it is evident in FIG. 12, if, while the cutter is in its position A the wheel 45 or wheels 9a are displaced (together with the carriage 8a, which is not represented in FIG. 12) in the direction shown by arrow 7 until the position represented in said FIG. 12 is exactly reached, that is to say until the plane which passes through the respective bottom lands 38 of 50 gear blanks 9a is tangent to the cutting edge 36b, and the gear blanks 9a remain in this position during the whole cutting reciprocating cycle above described, while the gear cutter successively passes by the positions A, A₁, B, B₁ and A, the teeth of the wheels 9a will be cut during 55 the same cycle by cutting edge 36b.

70 In fact, examining now only the cutting action on the teeth of gear or gears 9a, it will be evident that the position B of the cutter 9, which is the final position of the cutting of gears 9, is also the initial position of the cycle

for cutting gears $9a$ and so on, since the cycle of cutting gears $9a$ lags behind the cycle of cutting wheels 9 . The cutting time is so reduced to half the time required in the conventional methods, in such a manner that all the other conditions remaining unchanged, it will be possible, by using the method and apparatus of the present invention, to cut two gears in the same time that is necessary to cut one gear by the conventional methods. This is due only to the fact that in the new method the turning axis $X-X$ of the cutter 11 forms a suitable angle α with the turning axes $Y-Y$ and Y_a-Y_a of the gear blanks; and to the fact that the cutter used is a suitably characterized cylindrical wheel, like a simple pattern gear wheel or master gear.

Besides the above stated, the new method allows to save the time normally required for mounting and removing the pieces on and from the machine, as a result of which, the time of useful work of the machine is increased and additional production capacity is obtained.

Saving the aforesaid time is possible because the cut gears may be removed from one work station and new gears to be cut may be mounted on this station while on the other station are being cut the gears previously mounted.

A further increase of productivity is due to the fact that all the required movements in the cutting gears process as applied to the new machine are performed, as stated in the above description, by a substantially reduced number of movable members; as a result of this fact, the movable members may be more suitably dimensioned and the machine constitutes a rigid whole, free from vibrations, and permits heavier work.

The new method for cutting teeth may be applied to the production of straight or helicoidal teeth racks, by only making in the generation station of the above described new cutting gears machine some specific modifications.

In fact, if the circular movement of the wheels 9 and $9a$ is transformed into a linear movement, by means of the device represented in FIG. 13 suitably adapted to carriages 8 and $8a$ and if on this device is mounted a bar of suitable shape $50f$, it will be possible to cut teeth in said bar, the generated profile of which will be the profile of a toothed rack bar with the same cutting angle and the same pitch as the cutter.

Notwithstanding that said supporting arrangement for the bar is not an object of this invention, the invented method is applied in view of the fact that the cutter still forms the above defined angle α with the piece to be cut and that the other required generation conditions are maintained.

The new method is also applied to new generating machines for straight or helicoidal toothed rack bars, said machines having new characteristics which constitute one of the objects of the invention.

The new generating machine for straight rack bars is diagrammatically represented in FIGS. 15 and 16 of the appended drawings, by way of non restrictive example.

The base 39 supports the working bed 40 , similar to the beds commonly used in machine tools. The machine bed 40 is provided with prismatic guides 41 , parallel to each other, the longitudinal axes of which are contained in planes parallel to the direction of the rack bar generation movement, marked by arrows Y_3-Y_4 .

The bed 40 is provided, at one of its ends, with a plane surface 42 parallel to the axis of the prismatic guides 41 ; on this surface is disposed the main head stock 43 , similar to the head stocks commonly used in machine-tools; said head is so disposed that the shaft 44 can rotate about a turning axis $g-g$ parallel to the direction of the racks generation movement, marked by arrows Y_3-Y_4 . The turning axis $g-g$, also called center line, is located in a plane parallel to the plane of the longitudinal axis of the prismatic guides 41 and will be called

hereinafter "generation plane $G-G$ " (see FIGS. 15, 16, 17, 18, 19).

The tail stock 46 , together with the bracket block 45 , can slide along the prismatic guides 41 in either the two directions marked by arrows Y_3-Y_4 , in such a way that the geometric axis of the center 47 , which is fixed to the tail stock 46 , always coincides with the center line $g-g$, in any position of the tail stock 46 along the prismatic guides 41 .

Consequently, the geometric axis of the point 47 will be always contained in the generation plane $G-G$.

A cylinder 49 of suitably dimensioned external radius R is fixed to the flange 48 , which is fixed to the shaft 44 —this shaft being supported by head stock 43 —and turns on the center 47 . Cylinder 49 can rotate together with the shaft 44 with its geometric axis coincident with the turning axis and with the center line previously defined.

In this way any radial plane which contains the geometric axis of the cylinder 49 will pass through the center line $g-g$. The particular radial plane which is parallel to the plane of the prismatic guides 41 will coincide with the generation plane $G-G$ above defined.

All the generating lines of the cylinder 49 will be further parallel to the center line $g-g$.

On the cylinder 49 are mounted several prismatic bars 50 , of rectangular cross section which will be hereinafter named rack blanks 50 . These bars are so disposed that their geometric longitudinal axes are parallel to the axis of the cylinder 49 and therefore parallel to the direction of displacement marked by arrows Y_3-Y_4 ; and that two faces of the rack blanks 50 are parallel to the corresponding radial plane passing through the respective longitudinal axis of the blank, while the two other faces are parallel to the corresponding plane passing through the respective longitudinal axis and tangential to the cylinder 49 .

The rectangular cross section of the rack bars is assumed only for explanations purposes, but does not restrict the present invention because the cited cross section may be of any shape.

Under these conditions, during the rotary movement of the cylinder 49 , when the radial plane associated with any one of the racks blanks 50 coincides with the generation plane $G-G$, this particular rack blank will have two faces parallel to the generation plane $G-G$ and the two other faces parallel to a plane which is perpendicular to the generation plane $G-G$ and which will be called "reciprocating plane $R-R$."

All the racks, therefore, will be generated at the moment when they reach the particular above defined position, which will be called "generation position" (see FIG. 18).

A carriage 51 with an apron 52 is movable in either the two directions indicated by the arrows Y_3 and Y_4 , and supported and guided by the prismatic guides 41 . On apron 52 are mounted the driving mechanisms for movement in the direction Y_3-Y_4 ; this movement is hereinafter called "displacement movement for rack generation" and is suitably synchronized with the rotatory movement of cylinder 49 and with the rotatory movement of the rack cutter $11a$, as will be better explained below.

On the carriage 51 (FIG. 16) is fixed the slide 53 which can be transversely moved in either the two directions shown by the arrows $6b$ and $7b$. This movement is caused by means of the hand operated crank 54 .

On the table 53 is fixed the auxiliary head 55 , which supports the cutter $11a$, substantially similar to the cutter 11 used in the new gear cutting machine previously described. The cutter $11a$ which can rotate about axis $X-X$ is mounted on the auxiliary head 55 in such a manner that any plane perpendicular to the turning axis $X-X$ makes a constant angle α with the generation plane $G-G$ above defined, the intersection of the particular

one of said planes which contains the cutting face 34b of the cutter 11a being a line Z—Z which lies in the generation plane G—G and is parallel to the longitudinal axis Y₃—Y₄ of the rack blank 50 (FIG. 18).

As a result of the above stated, the turning axis X—X will be contained in a plane which makes the same inclination angle α with the reciprocating plane R—R above defined (see FIG. 18).

To sum up, the cutter 11a is rotatable about its axis X—X and shiftable in either the two directions marked by arrows Y₃ and Y₄, together with the carriage 51, these two movements being synchronized with the rotary movement of the cylinder 49 about the center axis g—g, as will be later explained; the cutter 11a can also be moved together with the table 53 in either the two senses marked by arrows 6b and 7b.

The synchronization of the three main movements which are required for the generation of racks in accordance with the new method, as applied to the new straight teeth racks generating machine under discussion, namely: rotary movement of cylinder 49 about the center axis g—g, rotary movement of cutter 11a about its axis X—X, and displacement of cutter 11a in either the two directions marked by arrows Y₃ and Y₄, is obtained as follows by the machine shown in FIG. 15.

The power of the electric motor 56 is transmitted over the belts 57, pulleys 58, intermediate shaft 59 and speed changing gears 60 to the shaft 44. From this shaft 44 and over the gears 61a of the gear box 61, the movement is transmitted to a pair of bevel gears 62, coupled to the rod 63; this rod will therefore rotate in a suitable relationship with the shaft 44 and consequently with the cylinder 49, which is fixed to said shaft 44. This suitable relationship will depend upon the selection of the gears 61a in the gear box 61. The rod 63 is used for transmitting the rotatory movement of cutter 11a about its axis X—X and for displacing the cutter 11a together with carriage 51 and apron 55 in either the two senses marked by arrows Y₃ and Y₄ as will be seen later.

The rod 63—which has through almost all its length an axial groove 63a—transmits the movement to the worm screw 64, which is coaxial with the rod 63 and is mounted on the apron 52 in such a manner that it can axially slide along the rod 63 together with said apron 52 in either the two senses indicated by the arrows Y₃ and Y₄.

The endless screw 64 transmits the movement to the worm screw 66, over the change gears 65. Worm screw 66 is coupled to the helicoidal crown gear 67, fixed to the shaft 68, on which is mounted the cutter 11a.

Power and movement are thus transmitted from shaft 44 to the cutter 11a.

Due to the transmission of power and rotary movement over the aforesaid gear box 61, bevel gears 62, rod 63, worm screw 64, change gears 65, worm screw 66, and crown gear 67 of the shaft 68 to the cutter 11a in a predetermined relationship, the cutter 11a and the cylinder 49 will rotate in a timed relationship.

The rod 63, by means of its end 63b, transmits the movement to the gears of the gear box 69, from which the movement is retransmitted over the gears and shafts therein contained to the threaded arbor spindle 70 in a suitable relationship. This threaded arbor spindle and the cooperating nut 71, fixed to the apron 52, performs the displacement of the cutter 11a, which is carried together with the supplementary head or support 55, the table 53, the carriage 51 and the apron 52, in either the two senses marked by arrows Y₃ and Y₄.

The transmission of power and movement from the rod 63 over gears and shafts 69a of the gear box 69, threaded arbor spindle 70, nut 71 and apron 52 to the cutter 11a is effected at a predetermined relationship with the angular speed of the rotating cylinder 49 so that the cutter 11a will move in either the two senses in a timed relationship with the rotary speed of cylinder 49.

Since the transmission of the rotary and linear movements of the cutter 11a is effected, as above stated, in such a manner that it is possible to change the speed ratios by means of change gear boxes 61, 65 and 69, the new machine can produce with a cutter of suitably determined characteristics a large number of racks with different pitches, pressure angles and depths.

In order to perform rapid displacement movements for adjusting and presetting purposes, there is provided an auxiliary motor 72, by means of which the threaded arbor spindle 70 may be operated, over the gear and shafts 69a of gear box 69 and independently of rod 63, which can be disengaged from box 69, before starting the motor 72. On finishing the desired rapid movement and disconnecting the motor 72, the rod will be reengaged to the gear box 69 by moving the lever 73 in the direction of the arrow 74. A locking device (neither described nor represented) which does not form part of this invention is provided in order to avoid the simultaneous and antagonistic transmission of rotary movements from motor 72 and rod 63 to the gear 69a.

In this way, when the lever 73 has been replaced into its normal working position, as indicated by arrow 75, said locking device automatically prevents the energizing of motor 72.

The new machine for cutting helicoidal teeth racks according to new method for cutting teeth is quite similar to the above described new machine for cutting straight teeth racks which is represented in FIG. 17, no changes being noted in the relative position of the cylinder 49, rack blank 50 and cutter 11b.

The main differences between the new machine for cutting helicoidal teeth racks and the new machine for cutting straight teeth racks are relative to the cutter 11b, which has helicoidal teeth instead of straight ones, and to the transmission and relationship of the movements of the cylinder 49 and cutter 11b.

In fact, to meet the conditions of movement transmission which are required for helicoidal racks generation purposes it will be necessary to make the displacement of the racks to be cut in either the direction marked by arrows Y₃ and Y₄ equal to the displacement on the pitch circle of the cutter during its rotary movement and, at the same time, equal to the displacement of the same cutter in either the two directions marked by arrows Y₃—Y₄, depending upon the sense of development of the helix and upon the sense of the rotary movement of the cutter.

In practice, the above conditions are satisfied by the new racks cutting machine, as shown in FIG. 17, which is an exemplary embodiment given only for explanation purposes.

The motor 76 transmits power and movement to the rod 78 over the gears 77; this rod 78 is provided, in almost all its length, with a longitudinal groove 78a.

One of the ends 78b is coupled—by means of the coupling gear 79, over lever 80 when this is moved in the direction indicated by arrow 81—to the gears 83 within a gear box 84; over these gears 83 the movement is transmitted to the shaft 44 and from this to the cylinder 49, on which are mounted the rack blanks 50. The cylinder 49, therefore, rotates together with the shaft 44, in a suitable speed relationship with the rod 78. Along the rod 78 can slide the gear wheel 85 which is supported by the apron 52a. Said gear wheel is coupled to a set of change gears 86, also supported by the apron 52a and which transmit the movement to the gear wheel 87 mounted on the apron 52a. The gear wheel 87 is coupled to the threaded arbor 88, which is fixed to the bed of the machine by means of pins 89b and 89c provided in the bearings 89 and 89a, thus absolutely preventing any movement. Gear wheel 87, on turning about its geometric axis which coincides with the geometric axis of the threaded arbor 88, is forced to move in either the

two senses marked by arrows Y_3-Y_4 , together with the apron 52a and the cutter 11b.

The transmission ratio between the movements of the cutter—in either the two senses of linear displacement marked by arrows Y_3-Y_4 and in either the two senses of revolution marked by arrows Y_5 and Y_6 —and the rotary movement of the cylinder 49 is determined by the pitch and sense of the rack blanks helix, by the circular pitch of cutter 11b, and by the number of revolutions of cylinder 49 needed to generate in the rack blanks 50 a complete pitch, similar to the cutter pitch.

Said relationship between the above mentioned movements will be obtained by means of suitable combination of the change gears 90 in the gear box 91, gears 68 on the apron 52a and gears 83 in the gear box 84.

The end 78c of the rod 78 is coupled to the gears 90 of the gear box 91, from which power and movement are transmitted to a rod 92 provided in almost all its length with a groove 92a. On rod 92 is slidably mounted by means of a forelock 93 an endless worm screw 94 which is fixed to apron 52a.

The worm screw transmits its rotary movement to the helical crown gear 95, to which is coupled the cutter 11b by means of the shaft 95a.

The transmission of the rotary and linear movements of the cutter 11b is effected, as above stated, in such a manner that the speed ratios can be changed by means of the change gears 83, 86 and 90, so that it is possible to produce with any cutter 11b having suitably determined characteristics, a large number of different racks.

In order to achieve adjustments and manual operation of the apron 52a, a hand wheel is provided on the apron. This hand wheel is coupled to a pair of bevel gears 96 which are coupled by means of a gear wheel 97 to the gear wheel 85. The gear wheel 85 is driven after disengaging the rod 78 from the gears 83. This disengagement is obtained by moving lever 80 in the direction marked by arrow 82 and after spacing the cutter 11b from the cylinder 49 in the direction marked by arrow 7b (FIG. 16).

The cutter 11a used in the new machine as previously described is represented in FIGS. 14c and 14d and is similar to the cutter 11 represented in FIGS. 14a and 14b, the difference between them being that the cutter 11a has a conical surface 35 only in the face 34b, while the cutter 11 has two conical surfaces, one on each face, as shown in FIG. 14b.

This conical surface the geometric axis of which coincides with the turning axis of the cutter 11a is obtained by sharpening the cutter 11a, in such a manner that the intersections of said conical surfaces 35 with the teeth 36 form the cutting edges of the cutter 11a.

Referring now to FIGURES 18 and 19, which represent the relative positions of the cutter 11a and the rack blank 50 as above defined in connection with the new method as applied to the new cutting machines for straight and helicoidal teeth racks, and calling said relative position generation position, the rack teeth cutting operation will now be described. For explanation purposes and without restricting the invention, the description will be made only in connection with straight teeth racks.

The cylinder 49 turning about the axis $g-g$ in synchronism with the revolutions and displacement of the cutter, as above stated, each rack blank 50 on the cylinder 49 passes through the generation position previously defined.

The cutter 11a was moved in the direction of arrow 6b by means of the crank 54, not represented in FIGURES 18 and 19, until such a position was reached that the cutting edges 36b of the teeth 36 became tangent to a plane R_1-R_1 , parallel to the reciprocating plane $R-R$ and placed in generation position at a distance E from the face 50a of rack 50. This distance E represents the desired height of the teeth 50c of the rack to

be cut. In other words, the cutter 11a was moved until a cutting position for a given cutting depth E was reached. The cutting edge 36b will then be at the position marked C in FIG. 19.

At this position, if the rack is supposed to be moving in the direction of arrow Y_1 and Y_2 (disregarding for a while the rotary movement of the rack about the centers line $g-g$) the faces 50a and 50b being kept—during this movement—parallel to the reciprocating plan $R-R$, the cutting edge 36c of the cutter 11a—during the rotary movement of the cutter about the turning axis $X-X$ —will generate in the rack to be cut the straight profile $C''-A''$ while the cutting edge 36b will generate the bottom of tooth of the rack $C-B'$, which is coincident with the plane R_1-R_1 . The supposed movement of the rack in the directions Y_1 and Y_2 would correspond to the main reciprocating movement already described in connection with the gear cutting machine; and as the cutter is moving in the sense of arrow Y_3 and Y_4 , the rack 50 would be generated.

Considering now that the rack actually rotates together with the cylinder 49 about the center line $g-g$, the assumed conditions are reproduced for every section of the rack 50 such as for instance the sections formed by the radial planes G_1-G_1 , G_2-G_2 , G_3-G_3 and others, when these sections coincide with the generation plan.

On rotating cylinder 49, therefore, at the instant when a particular plane G_r-G_r among the infinite number of possible planes coincides with the generation plan $G-G$, the cutter 11a, which is rotating about the axis $X-X$ and moving in either the two senses Y_3-Y_4 in the generation plan $G-G$, will generate a straight profile $C''-A''$. The generated rack, therefore, has the same profile in every section with one of the radial planes G_r-G_r .

This particular characteristic, which is peculiar to the racks generated in the new machine, constitutes one of the new and proper characteristics of the machine, absolutely unknown up to day. As a result of the above cited characteristic, it is possible, by using the new machine and following the new method, to automatically execute some finishing operations without using additional equipment, as were needed with the known methods and machines. In fact, as a result of the above stated, if a section of the rack generated with planes parallel to the reciprocating plan $R-R$ is considered, said planes being the ones where the engagement is performed when the rack is coupled with its respective gear wheel, it will be noted that said section has the shape represented in section $P-P$ of FIG. 19b. This figure represents the section of a rack teeth with the engagement plane PP passing through the point P of rack 50.

It will be evident that the section has the shape illustrated FIG. 19b from the following considerations:

The thickness of the teeth has been considered in the intersection of the medium section $C-A$ of the rack 50 and the generation plan $G-G$ and in the faces $50d$ and $50e$, which are parallel to the generation plan.

The thickness N at point C will be equal to the thickness at point C' , because these points have been generated with the same radius r_c of the cutting edge 36c, or, in other words, because the points C and C' are located on the same circumference. Similar considerations may be done with respect to points B and B' , P and P' , A and A' , and to every point of the parallel sections considered, which are located on the same circumferences, and in which the thickness of the teeth will be respectively N , N_1 , N_2 , N_3 .

Considering now the section in engaging planes parallel to the plane R_1-R_1 and passing through points C , B , P and A , to the point C will correspond, on the considered plane, the point B' ; to the point B , will correspond the point P' ; and to the point P will correspond the point A' . Examining now the thickness of the teeth

in the intersection of planes parallel to the reciprocating plane $R-R$, with planes parallel to the generation plane $G-G$, it will be noted that said thickness is variable, the thickness at B being greater than the thickness at the corresponding point B' . It is evident, therefore, from FIG. 19, that in any plane of engagement the section is similar to the one represented in FIG. 19b. In the flanks of the teeth a desirable bulge or crowning will be automatically produced by the new machine and method without using the specific additional equipment which is needed in other known machines and methods.

Besides the above cited specific characteristics, the new rack generating machine in accordance with the invention, has the remarkable advantage that with said machine it is possible to cut simultaneously all the rack blanks mounted on cylinder 49, in the same time that was required to cut one rack by the conventional methods. The number of rack blanks 50 which can be mounted on cylinder 49, as well as the crowning produced is, obviously, a function of the radius R of the cylinder 49 and of the size of the racks to be generated and are limited only by the capacity of the machine.

As above stated in discussing the new machine for cutting cylindrical gear wheels with straight or helicoidal teeth and the new machine for cutting racks with straight or helicoidal teeth, the cutter used is a gear wheel of suitable characteristics which are selected in relation to the series of gear wheels or racks to be generated as is usual in the conventional processes, the axis of said cutter forming an angle α with the piece to be cut, in the position clearly defined for each case.

The flanks of the teeth of the gear wheel used as cutter have not any special surface but have the same surface that is usually found in any cylindrical gear wheel, this surface being obtained by the usual methods for manufacturing cylindrical gear wheels, and by using the standard machines usually employed to cut and to rectify precision cylindrical gear wheels.

The necessary relief and clearance angles for the cutting action of the cutting edge which is obtained by grinding a conical surface coaxial with the cutter turning axis, are automatically obtained as a result of the position of the cutter with respect to the piece to be cut; this position has been clearly defined in the preceding discussion and constitutes one of the main objects of the invention.

Referring now to FIG. 20, it will be noted that as a result of the existing clearances, it is not necessary to make the relief and clearance angles in the cutter. All facts which will be stated are valid for all applications of the method, and the description of a cylindrical gear does not involve any limitation of the invention.

FIG. 20 shows the relative position of the cutter 11 and of the gear blank 9, as previously described in connection with the new machine for cutting gears. It is evident that the frontal clearance between the bottom 36b of the tooth to be cut and the head 37 of the cutting tooth, which is needed to ensure the free cutting action of the cutting edge 36b is automatically provided as a result of the inclination angle α of the cutter turning axis $X-X$ with respect to the gear blank turning axis $Y-Y$. The end relief angle is the same angle α .

The lateral clearance at the cutting edge flanks is also automatically provided by means of said α inclination angle and as a result of the tooth involute profile shape. As a matter of fact, it is known that the width of the involute profile tooth varies from base to head, the tooth head being thinner than the tooth base.

If several teeth profiles, obtained by intersection of planes G_4-G_4 and G_5-G_5 , parallel to the generation plan, with the tooth 36, are projected on the generation plane GG , it will be seen, as it is evident from FIGS. 20 and 20a, that in the reciprocating plane RR , which contains the directions Y_1 and Y_2 of the main reciprocating

movements previously described, and in any plane parallel to the same passing through the teeth 36, the width of the tooth 36 is a maximum at the intersection of said planes with the generation plane $G-G$, the width being always smaller at the intersection of planes located above the generation plane as, for instance the plane G_4-G_4 , G_5-G_5 , and so on. Considering the plane $R-R_1$, for instance, it will be seen that the tooth 36 has a width H_3-H_3 at the intersection with plane $G-G$; a width I_1 smaller than H_3 , in the plane G_4-G_4 ; and a width V_1 , still smaller than I_1 and than H_3 , in the plane G_5-G_5 . The above stated clearly demonstrates that the lateral clearance which is needed for the suitable cutting action of the cutting edges of teeth 36 is obtained consequently to the inclination of the axis $X-X$, as previously defined.

It is obvious that in order to provide the required clearance it is not necessary to create involute helicoidal surfaces at the flanks of the teeth, as well as other known inconveniences, which are completely avoided by the present invention, because the flanks of the used cutter 11 are similar to the flanks of any cylindrical gear wheel with involute profile teeth.

Due to the fact that the teeth of the cutter have the same profile and thickness in any section in planes perpendicular to the turning axis $X-X$, the successive sharpening operations do not alter the profile and the thickness of the teeth and consequently the working conditions of the cutter 11 will remain unchanged during all its useful life.

In order to more clearly explain the above stated, references will be made now to FIG. 21 in examining the work conditions of the cutter 11 in two different phases of its useful life.

It is assumed that the cutter has, at a given phase of its life, a thickness F , and a sharpening cone with angle β and radius r , this radius being also the distance from center O to the point of contact of the cutting edge 36a with the bottom land 37 of the teeth. The projection of said distance on generation plane $G-G$ is equal to L_1 .

Considering the engagement conditions during the cutting action in the engagement plan P_1-P_1 , which is tangent to the pitch circle 9_f of the blank gear 9, it is noted that the contact takes place at point P_2 of the cutting edge, the point P_2 being located on the pitch circle of the cutter 11.

Obviously this point is also located on the pitch circle 11_p of the equivalent cutter 11_e and constitute the contact point P_3 of the pitch circles 9_p and 11_p , with the engagement plane P_1-P_1 , the intersection of which with the generation plane $G-G$ is represented by the straight line P_4-P_4 .

The equivalent cutter 11_e and the gear blank 9 will work, therefore, under the above described engagement conditions with a pressure angle Φ . This angle Φ is also the operating or cutting pressure angle in the generation plane $G-G$.

It is assumed now that the cutter 11 in any other phase of its life has a thickness f , smaller than the thickness F , previously assumed. The cutter of thickness f will be heretofore named cutter 11c.

It is easy to see that only the thickness of the cutter 11c has changed with respect to cutter 11; the sharpening cone angle β , the radius r , the distance L_1 , the position of point P_2 with respect to plan P_1-P_1 , the equivalent cutter 11_e and the point P_3 of contact of the cutting edge with the gear blank remain unchanged.

In this phase of the cutter's life the cutting action in the generation plan $G-G$ will take place with the same operating or cutting pressure angle Φ , which will be constant during all the useful life of the cutter 11.

This particular characteristic of the cutter used in the new method is absolutely peculiar to it and is a result of the cutter being a gear wheel of suitable characteristics, with its turning axis inclined through a predetermined angle with respect to the piece to be cut.

Having thus described and represented my invention, what I claim is:

1. Gear cutting machine comprising, in combination, first support means, and second support means, one of said support means being movable in one direction relative to the other of said support means; at least one rotary holder means for holding at least one gear blank, and being mounted on said first support means for rotation about a first axis parallel to said direction; rotary cutter gear means having a second axis of rotation inclined at an acute angle to said first axis, said rotary cutter means being mounted on said second support for movement in direction of said second axis and to and from a position adapted to mesh with a gear blank held by said holder means; and operation control means for rotating said cutter gear means and for alternately reciprocating in a timed sequence said one support means in direction of said first axis, and said cutter gear means in direction of said second axis.

2. Gear cutting machine comprising, in combination, first support means, and second support means, one of said support means being movable in one direction relative to the other of said support means; at least one rotary holder means for holding at least one gear blank, and being mounted on said first support means for rotation about a first axis parallel to said direction; rotary cutter gear means having a second axis of rotation inclined at an acute angle to said first axis, said rotary cutter means being mounted on said second support for movement in direction of said second axis and to and from a position adapted to mesh with a gear blank held by said holder means; and operation control means for rotating said cutter gear means, and for moving in a timed cycle of operations said one support with said cutter means in said one direction during a cutting stroke, for retracting said cutter gear means on said second support in direction of said second axis away from said holder means and said gear blank, for returning said one support means in said one direction, and for advancing said cutter gear means on said second support means in direction of said second axis toward said holder means and said gear blank, and for holding said one support means stationary during retraction and advance of said cutter gear means in direction of said second axis so that said cutter gear means and the gear blank in said holder means perform a relative movement along a parallelogram having a pair of opposite acute angles and a pair of opposite obtuse angles.

3. Gear cutting machine comprising, in combination, first support means and second support means, one of said support means being movable in one direction relative to the other of said support means; a pair of rotary holder means for holding, respectively, a pair of gear blanks, and being mounted on said first support means for rotation about a pair of parallel first axes parallel to said direction; rotary cutter gear means having a second axis of rotation inclined to said first axes and being located in a common plane with the same, said rotary cutter means being mounted on said second support for movement in direction of said second axis and to and from two positions adapted to mesh with gear blanks held by said pair of holder means, respectively; and operation control means for rotating said cutter gear means, and for reciprocating said one support means in direction of said first axes, and said cutter gear means in direction of said second axes in a timed cycle of operations so that one of said gear blanks is cut during a first stroke of said one support means, and the other gear blank is cut during the return stroke of said one support means.

4. Gear cutting machine comprising, in combination, first support means and second support means, one of said support means being movable in one direction relative to the other of said support means; a pair of rotary holder means for holding, respectively, a pair of gear blanks, and being mounted on said first support means

for rotation about a pair of parallel first axes parallel to said direction; rotary cutter gear means having a second axis of rotation inclined to said first axes and being located in a common plane with the same, said rotary cutter means being mounted on said second support for movement in direction of said second axis and to and from two positions adapted to mesh with gear blanks held by said pair of holder means, respectively, said cutter gear means including a cylindrical cutter gear having at opposite ends thereof conical recessed surfaces forming two cutting edges with the teeth of said cutter gear; and operation control means for rotating said cutter gear means, and for reciprocating said one support means in direction of said first axes, and said cutter gear means in direction of said second axes in a timed cycle of operations so that one of said gear blanks is cut during a first stroke of said one support means by one of said cutting edges, and the other gear blank is cut during the return stroke of said one support means by the other of cutting edges.

5. Gear cutting machine comprising, in combination, first support means and second support means, one of said support means being movable in one direction relative to the other of said support means; a pair of rotary holder means for holding, respectively, a pair of gear blanks, and being mounted on said first support means for rotation about a pair of parallel first axes parallel to said direction; rotary cutter gear means having a second axis of rotation inclined to said first axes and being located in a common plane with the same, said rotary cutter means being mounted on said second support for movement in direction of said second axis and to and from two positions adapted to mesh with gear blanks held by said pair of holder means, respectively; and operation control means for rotating said cutter gear means and said holder means, and for moving in a timed cycle of operations said one support with said cutter means in said one direction during cutting stroke for cutting one of said gear blanks, for moving said cutter gear means on said second support in direction of the second axis away from the holder means holding the cut gear blank, for returning said one support in said one direction in another cutting stroke for cutting the other of said gear blanks, and for moving said cutter gear means on said second support means in direction of said second axis away from the last mentioned holder means and toward the first mentioned holder means and said first mentioned gear blank, and for holding said one support means stationary during said movements of said cutter gear means in direction of said second axis.

6. Gear cutting machine, comprising, in combination, a stationary support means, and a movable support means mounted on said stationary support means for movement in one direction; at least one rotary holder means for holding and turning at least one gear blank means and being mounted on said stationary support means for rotation about a first axis parallel to said direction; cylindrical rotary cutter means having a second axis of rotation inclined at an acute angle to the first axis and being mounted on said movable support for movement in direction of said second axis and to and from a position adapted to mesh with a gear blank held by said holder means; and operation control means for rotating said cutter gear means and said holder means, and for moving in a cutting stroke said movable support means in direction of said first axis while stopping movement of said cutter means in direction of said second axis, for withdrawing said cutter means in direction of said second axis while stopping movement of said movable support means, for returning said movable support means with said cutter means in direction of said first axis, and for advancing said cutter means in direction of said second axis toward said gear blank while stopping movement of said movable support means so that said cutter gear means and the gear blank in said holder means perform a rela-

tive movement along a parallelogram having a pair of opposite acute angles and a pair of opposite obtuse angles.

7. Gear cutting machine comprising, in combination, a stationary support means, and a movable support means mounted on said stationary support means for movement in one direction; a pair of rotary holder means mounted on said stationary support for holding and turning, respectively, a pair of gear blank means, said rotary holder means being respectively turnable about a pair of first axes parallel to said direction; rotary cutter means having a second axis of rotation inclined to said first axis and located in a common plane with same, said rotary cutter means being mounted on said movable support for movement in direction of said second axis and to and from two positions adapted to mesh with gear blanks held by said pair of holder means, respectively; and operation control means for rotating said cutter gear means and said holder means, and for moving in a first cutting stroke on one of said gear blanks said movable support means in direction of said first axes while stopping movement of said cutter means in direction of second axis, for moving said cutter means in direction of said second axis away from said one gear blank and toward the other gear blank while stopping movement of said movable support means, for returning in a second cutting stroke on the other gear blank said movable support means with said cutter means in direction of said first axes, and for moving said cutter means in direction of said second axis from said other gear blank toward said one gear blank while stopping movement of said movable support means.

8. Gear cutting machine comprising, in combination, a stationary support means, and a movable support means mounted on said stationary support means for movement in one direction; a pair of rotary holder means mounted on said stationary support for holding and turning, respectively, a pair of gear blank means, said rotary holder means being respectively turnable about a pair of first axes parallel to said direction; rotary cutter means having a second axis of rotation inclined to said first axis and located in a common place with same, said rotary cutter means being mounted on said movable support for movement in direction of said second axis and to and from two positions adapted to mesh with gear blanks held by said pair of holder means, respectively, said rotary cutter means including a cylindrical cutter gear having at opposite ends thereof conical recessed surfaces forming two cutting edges with the teeth of said cutter gear; and operation control means for rotating said cutter gear means and said holder means, and for moving in a first cutting stroke with one of said cutting edges acting on one of said gear blanks said movable support means in direction of said first axes while stopping movement of said cutter means in direction of said second axis, for moving said cutter means in direction of said second axis away from said one gear blank and toward the other gear blank while stopping movement of said movable support means, for returning in a second cutting stroke with the other of said cutting edges acting on the other gear blank said movable support means with said cutter means in direction of said first axes, and for moving said cutter means in direction of said second axis from said other gear blank toward said one gear blank while stopping movement of said movable support means.

9. Gear cutting machine comprising, in combination, a stationary support means, and a movable support means mounted on said stationary support means for movement in one direction; a pair of rotary holder means mounted on said stationary support for holding and turning, respectively, a pair of gear blank means, said rotary holder means being respectively turnable about a pair of first axes parallel to said direction; rotary cutter means having a second axis of rotation inclined to said first axis and located in a common plane with same, said rotary cutter means being mounted on said movable support for movement in direction of said second axis and to and from two positions adapted to mesh with gear blanks held by said pair of holder means, respectively, said rotary holder means being mounted on said stationary support for movement toward and away from each other in said common plane and in a direction perpendicular to said first axes; and operation control means for rotating said cutter gear means and said holder means, and for reciprocating said movable support means in direction of said first axis while stopping movement of said cutter means in direction of said second axis, and for reciprocating said cutter means in direction of said second axis while stopping movement of said movable support means in direction of said first axis, whereby said gear blanks are respectively cut during reciprocating movement of said movable support means.

10. A machine for cutting gear teeth, comprising, in combination, first support means, and second support means, one of said support means being movable in one direction relative to the other of said support means; at least one rotary holder means for holding and supporting at least one gear blank, and being mounted on said first support means for rotation about a first axis parallel to said direction; cylindrical rotary cutter means having a second axis of rotation inclined at an acute angle to said first axis and being mounted on said second support; and operation control means for rotating said cutter gear means and for alternately reciprocating in a timed sequence said one support in the direction of said first axis, and for moving said cutter gear means and said first support means relative to each other in the direction of said second axis so that said cutter gear means and the gear blank in said holder means perform a relative movement along a parallelogram having a pair of opposite acute angles and a pair of opposite obtuse angles.
